Specification for Design.

Patented Mar. 15, 1921.

Application filed July 2, 1919. Serial No. 308,328. Term of patent 3½ years.

To all whom it may concern:

Be it known that I, WILLIAM R. ATKINSON, a citizen of the United States, residing at Harrisburg, in the county of Dauphin and State of Pennsylvania, have invented a new, original, and ornamental Design for an Emblem, Badge, Pin, Fob, Ring, or like Article, of which the following is a specification, reference being had to the ac-

companying drawing, forming part thereof, in which the figure is a plan view of an emblem, badge, pin, fob, ring, or like article, showing my new design.

I claim:

The ornamental design for an emblem, badge, pin, fob, ring, or like article, as shown.

WILLIAM ROSS ATKINSON.
